UNITED STATES PATENT OFFICE.

RILEY E. ANTHONY, OF OMAHA, NEBRASKA, ASSIGNOR OF ONE-HALF TO MARTIN K. NESHIER, OF LOS ANGELES, CALIFORNIA.

HEADLIGHT.

Application filed November 14, 1924. Serial No. 748,873.

To all whom it may concern:

Be it known that I, RILEY E. ANTHONY, a citizen of the United States, residing at Omaha, in the county of Douglas and State of Nebraska, have invented certain new and useful Improvements in Headlights, of which the following is a specification.

The present invention relates to motor vehicle headlights, and more particularly to headlights of the anti-glare type.

An object of this invention is to provide a device of this type which is adapted to project beams of light to any desired angle so that the headlight will conform to the different headlight laws in each municipality, county or State.

Another object of this invention is to provide a device which may be easily attached to the present headlights of motor vehicles without alteration in the body or casing of the lamp.

A further object of this invention is to provide a device which is easily and readily adjustable so that a motor vehicle moving from one jurisdiction to another where different headlight laws are in existence may have the headlights quickly adjusted to conform to the laws of the particular jurisdiction.

A still further object of this invention is to provide an anti-glare headlight which will adequately illuminate the roadway, but which will not project a beam of light beyond a predetermined point in advance of the vehicle, nor above a predetermined height.

A further object of this invention is to provide a device of this character which is symmetrical in design and when installed on a motor vehicle will add to rather than detract from the artistic outlines of the vehicle, the device presenting the appearance of a slightly elongated lamp which may be varied in size to conform to the proportions presented by the vehicle.

The above and various other objects and advantages of this invention will in part be understood from, and in part described in,

the following detailed description thereof, wherein:

Fig. 1 is a transverse section of a device constructed according to this invention taken substantially through the center thereof, and

Fig. 2 is a transverse section of the device taken substantially on line 2-2 of Fig. 1.

Referring to the drawings, and first to Fig. 1, 10 designates a lamp housing or casing of the conventional type in present use having a reflector 11 mounted therewithin. A lamp socket 12 is adapted to project through the casing 10 and the reflector 11, and a lamp 13 is adapted to fit into said socket 12 at its inner end, so that the lamp when lighted will have its rays or beams projected outwardly by said reflector 11.

An outer casing or housing 14 is adapted to fit into the outer end of the inner or main housing 10, and at its inner end abuts the outer end of said reflector, so that when the casing 14 is bolted, riveted or otherwise firmly secured to said casing 10, the inner end of said casing 14 holds the reflector 11 in adjusted position. At the outer end of the casing 14 there is secured a plate 15 which has an opening 16 therein to allow the light beams projected by said reflector 11 to pass therethrough. Abutting the outer surface of the plate 15 is a lens 17 which is preferably of the saw-toothed type, and the lens 17 is adapted to be held in position by a ring 18 which projects over the outer surface of said lens 17. The ring 18 may be detachably held in position by screws 19 or the like so that should the lens 17 become broken, it may be easily and readily replaced.

A ray deflector 20 is pivotally mounted within the casing 14 and is positioned rearwardly of the opening 16. A pair of pivotal rods or axes 21 is secured at opposite sides to the deflector 20 and project outwardly through the casing 14 so that the deflector 20 may be swung to any desired angle or inclination. The outer ends of the rods 21 are preferably threaded to receive a

nut 22 so as to prevent any lateral movement of the deflector 20. The bottom 23 of the deflector 20 has a groove 24 across the inner edge thereof to detachably receive a 5 lens 25 which is preferably of the saw-toothed type, and the top of the deflector 20 has a ridge 26 across the inner edge thereof spaced inwardly sufficient to form a seat for the upper edge of the lens 25. A 10 strap spring 27 is secured to the upper side of the top 28 of the deflector, and is preferably held in position by screws 29 or the like. The inner end of the spring 27 overhangs the inner edge of the top 28 and projects 15 downwardly sufficiently to engage the upper edge of the lens 25 so as to hold the same firmly against the ridge 26.

Within the deflector 20 are secured a plurality of deflector plates 30 which are held 20 in spaced relation to each other and are secured in the opposite sides of the deflector 20. The upper surface of the deflector plates 30 is preferably of non-reflecting material, and to answer this purpose may be 25 painted or enameled black or the like. The lower surface of the deflector plates 30 is preferably polished or the like so as to form an efficient reflecting surface. The plates 30 adjacent the bottom of the deflector 20 30 may be substantially parallel to the bottom, but the succeeding plates are inclined forwardly, the angle of inclination gradually becoming greater with each plate, and with the increased inclination of the plates the 35 spaces therebetween is successively diminished.

The beams of light which are projected forwardly by the reflector 11 strike the lens 25 as at 31. The beam is then projected 40 into the deflector 20, striking the upper surface of the plate 30 at approximately 32. The upper surface of the plate 30 being of non-reflecting material has the tendency to deaden the beam of light which is projected 45 on to the lens 17 at the point 33, and from this point the light is projected along the line 34. In a similar way a beam of light being projected from point 35 on the reflector 11 strikes the lens 25 at point 36 and 50 is projected straight through the lens into the deflector 20, striking the lower side of plate 30 at point 37. From point 37 the beam of light is projected without any decrease in its intensity through the lens 17 55 along the line 38 which is substantially parallel to the line 34.

The lines 34 and 38 which indicate the angle of inclination of the beams of light projected from the reflector 11 may be 60 varied by swinging the deflector upon its axis 21. In order to accomplish this adjustment a lug 39 is secured to the bottom of the deflector 20 and projects downwardly therefrom. A slideable plate 40 is 65 positioned on the inner surface of the

casing 14, and overlaps an opening 41 in the casing 14 which is large enough to slidably receive a bolt 42 or the like which is secured to the plate 40 and projects downwardly therefrom. A second upstanding lug 43 is secured to the inner side of the plate 40, and a link 44 is pivotally secured at one end to the lug 43 and at the opposite end to lug 39 by rivets 45 or the like. The movement either forward or backward of the bolt 42 thus rocks the deflector upon its axis 21 causing the beams of light to be projected either downwardly or upwardly. When the desired inclination of the deflector is found a nut 46 is tightened on the bolt 42, which prevents any movement of the bolt 42 in the slot or opening 41. It will be seen from the disclosure, this adjustment of the deflector may be effected without removing any of the component parts of the lamp, as it is simply necessary to loosen the nut 46 which is on the outer side of the casing 14 and then by moving the bolt either forward or backward the desired inclination of the light beams may be obtained.

It is of course understood that various changes and modifications may be made in the details of construction and design of the above specifically described embodiment of the invention without departing from the spirit thereof, such changes and modifications being restricted only by the scope of the following claims:

What is claimed is:

1. In a motor vehicle headlight, the combination of a casing, a deflector pivotally mounted within said casing, said deflector comprising a frame, a lens detachably secured to said frame, means for pivotally holding said deflector within said casing, deflector plates mounted within said frame and adapted to control the projection of light beams, a lug secured to the bottom of said frame and projecting downwardly therefrom, a plate slidably mounted within said casing, a lug secured to said plate and extending upwardly therefrom, a link pivotally connected to said first and second lugs, said casing having an opening therethrough, a threaded bolt secured to said plate and extending downwardly therefrom and through said opening in said casing, and a nut adapted to fit on said bolt for holding the same in a predetermined position within said opening.

2. In a motor vehicle headlight, the combination of a casing, and an adjustable deflector pivotally mounted within said casing, said deflector comprising a frame, a lens detachably mounted at one side of said frame, deflector plates mounted within said frame and adapted to control the projection of light beams, and adjustable means adapted to control the inclination of said deflector within said casing.

3. In a motor vehicle headlight, the combination of a casing, and an adjustable deflector pivotally mounted within said casing, said deflector comprising a frame, a lens dependently mounted at one side of said frame, deflector plates mounted within said frame, said deflector plates being positioned within said frame in spaced relation to each other, and adjustable means secured to said deflector and operable exteriorly of said casing for determining the angular inclination of said deflector with respect to said casing.
- In testimony whereof, I have affixed my signature.

RILEY E. ANTHONY.
